UNITED STATES PATENT OFFICE.

EDWARD L. HOPKINS, OF COLUMBUS, OHIO, ASSIGNOR TO THE JEFFREY MANUFACTURING COMPANY, OF COLUMBUS, OHIO, A CORPORATION OF OHIO.

MINING-MACHINE.

1,249,400.

Specification of Letters Patent. Patented Dec. 11, 1917.

Application filed September 9, 1913, Serial No. 788,853. Renewed October 27, 1917. Serial No. 198,898.

To all whom it may concern:

Be it known that I, EDWARD L. HOPKINS, a citizen of the United States, residing at Columbus, in the county of Franklin and 5 State of Ohio, have invented certain new and useful Improvements in Mining-Machines, of which the following is a specification, reference being had therein to the accompanying drawing.

10 The invention relates to side cutting mining machines and especially to machines of this class which are adapted for use in room and pillar mining. One object of the invention is the provision of a machine of 15 this character capable of cutting either toward the right or toward the left. A further object of the invention is the provision of improved cable feed devices. The invention has for another object the improvement 20 of the bed frame of the machine.

In the accompanying drawings, which illustrate a preferred form of construction embodying the invention,

Figure 1 is a plan view of the machine; 25 Fig. 2 is a left side elevation of the machine;

Fig. 3 is a vertical transverse section through the cutter frame;

Fig. 4 is an enlarged vertical transverse section on the line 4—4 of Fig. 1;

Fig. 5 is a vertical longitudinal section taken on the line 5—5 of Fig. 1;

Fig. 6 is an enlarged vertical transverse section on the line 6—6 of Fig. 1;

35 Fig. 7 is an enlarged vertical longitudinal section through the main shaft of the change speed gearing, the section being taken along the line 7—7 of Fig. 1;

Fig. 8 is a similar section through the 40 countershaft of the change speed gearing taken on the line 8—8 of Fig. 1;

Fig. 9 is an outer end elevation of the retarding drum;

Fig. 10 is a rear side elevation of the retarding drum;

Fig. 11 is a vertical longitudinal section 45 through the axis of the retarding drum;

Fig. 12 is a diagrammatic view showing the machine at the beginning of the entering 50 or sumping cut adjacent the right rib of a mine room;

Fig. 13 is a similar view showing the machine when the sumping cut is partially completed;

55 Fig. 14 is a similar view showing the ma-

chine at the end of the sumping cut and ready to start a side cut toward the left along the face of the coal;

Fig. 15 is a diagrammatic view showing the machine during the operation of undercutting toward the left along the face of the coal;

Fig. 16 is a diagrammatic view showing the machine at the beginning of a sumping cut adjacent the left rib of a mine room;

Fig. 17 is a diagrammatic view showing the machine during the operation of undercutting toward the right along the face of the coal.

The machine comprises a bed frame, a cutting apparatus which projects from the inner end of the bed frame, propelling and guiding devices mounted on the bed frame, and suitable driving connections between the motor and propelling devices and between the motor and cutting devices, respectively.

Referring in detail to the construction illustrated, the bed frame is composed of a bottom plate 1, preferably of rolled plate metal, and a top plate 2 having depending side walls 3 which are formed at their bottom edges with flanges which rest upon and are secured, as by rivets, to the bottom plate 1. The top plate 2 and the flanged side walls 3 are preferably cast in one.

Projecting from the inner end of the bed frame is a cutter frame designated as an entirety by 4. This cutter frame has two parallel sides spaced from each other to form a longitudinal slot, and these sides are made up of top plates 5, bottom plates 6 and intermediate spaced bars 7 which are secured together in any suitable manner, as by rivets (see Fig. 3). The space between the outer edges of the plates 5 and 6 forms a guide for a cutter chain 9. Ways are also formed between the inner edges of the plates 5 and 6 and these ways are adapted to fit over flanged projections formed on depending brackets 10 and 11 carried by the top plate of the bed frame. The sides of the cutter frame are connected at their front ends by suitable upper and lower plates 12 and 13 between which are mounted a sprocket wheel 14 over which the cutter chain passes. At the outer end of the cutter frame the cutter chain passes over a sprocket wheel 15 which is loosely mounted on an

upright shaft 16. This shaft has its lower end mounted on the bottom plate 1 of the bed frame and is preferably secured to the bottom plate by means of a base casting 17 riveted to said plate, the casting having an aperture in which the shaft is tightly fitted. The shaft 16 can be given further support in the manner indicated in Fig. 2 which shows the motor—presently to be 10 scribed—having its frame metal formed with a socket to receive the upper end of the shaft.

The cutter chain 9 can be of any desired construction as far as some features of my 15 invention are concerned, but to make it possible to readily change the machine so that it will cut toward the right instead of toward the left, or vice versa, I construct the chain in such a way that the bits can be 20 reversed in their sockets to permit the driving of the cutter chain in either direction. Referring to Fig. 1 it will be noted that the links 9^a of the chain have the sockets for the bits 9^b formed at right angles to the axis 25 of the chain. Hence, when it is desired to reverse the travel of the chain, it is only necessary to loosen the bits, withdraw them and insert them again in reversed position.

The machine is designed to be propelled 30 along the face of the coal during the cutting operation by a cable or the like, and upon the inner end of the bed frame is mounted a winding drum 18. A suitable draft cable 19 has one end secured to the winding drum 35 so that it can be wound upon the drum in either direction, the flange of the drum being formed with an aperture at 18° for the secured end of the cable that permits said cable end to swing, as indicated in Fig. 4, 40 so that the winding can be started in either direction. Furthermore, the machine is designed so that the cable 19 can be led off from the under side of the drum, either toward the left or toward the right, according 45 to the direction in which it is wound on the drum, the bed frame being provided at each side of the drum with a set of guide sheaves for the cable. These two sets of 50 guide devices are similar in all respects so that one description will apply to both. There are two horizontally arranged sheaves 20 and 21 having their peripheries spaced just far enough apart to permit the cable 55 to pass between them easily, and adjacent these sheaves is an elongated roller 22 which the cable passes over as it emerges from between the sheaves 20 and 21. The sheaves 20 and 21 are mounted on upright studs 23 and 24, respectively, and are secured by a 60 plate 25 and cotter pins 26. The roller 22 is mounted on a pin 27 which is carried by brackets or lugs 28 projecting from the side of the bed frame.

It will be seen that the feed cable, when 65 it is passed between the guide sheaves and

over the roller, can be deflected downward, or inward along the cutter frame or outward along the bed frame, so that any line of draft, which in practice it is desirable to apply to the machine, can be attained with 70 this construction, and that the bearing supports for the sheaves and the roller are rigid with the bed frame and can be made amply strong.

The drum 18 is mounted upon a longitudinally disposed shaft 29. This shaft is supported at its outer end by a bearing 30 of ordinary construction carried by the bed frame, and at its inner end by a bearing 31 which is carried by an upward buffer extension 32 formed on the inner end of the top plate 2 of the bed frame. The buffer 32 is disposed across the end of the bed frame and is rounded off somewhat at its ends as shown in Fig. 1. The buffer consists of a lower main part 32^a which is preferably cast in one with the top plate of the bed frame, and an upper detachable part 32^b which is bolted to the lower part. The division between the lower and upper parts 90 of the buffer is in a plane through the center of the bearing 31 so that the upper part of the buffer constitutes in effect the cap of said bearing.

The winding drum 18 is mounted loosely 95 on the shaft 29 adjacent a large spur gear 33 which is fast on said shaft. The drum is disengageably connected with the gear wheel and shaft by means of a clutch comprising a ring 18^b slidably mounted on the 100 hub of the drum, and a series of pins 18^c carried by the ring and arranged to extend through holes formed in the web of the drum 18 and in the web of the gear 33. By shifting the clutch ring on the hub of the 105 drum, the pins are withdrawn from engagement with the gear, whereupon the drum is free to turn upon the shaft.

34 is an electric motor mounted on the outer end of the bed frame with its armature shaft arranged longitudinally upon the machine. This motor, as to details of construction, may be of any preferred form but should be capable of being reversed so that it can be driven in either direction. 35 indicates a reversing switch for this purpose. The motor is designed to drive the winding drum 18 and the cutter chain 9. Any suitable form of transmission gearing can be provided between the motor and winding drum and between the motor and the cutting apparatus. In the construction shown the winding drum is driven by a train of gearing which comprises a bevel pinion 36 on the armature shaft of the motor, a bevel 115 gear 37 which meshes with the pinion and is fast on a vertical shaft 38. This shaft is mounted at its lower end in a bearing 39 carried by the bed frame and at its upper end in a bearing 40 formed in an upstand- 130

ing yoke 41 mounted on the top of the bed frame. Under the gear 37 and connected thereto by a friction clutch 37^a is a worm 42 which meshes with a worm wheel 43. 5 This worm wheel is fast on the end of a horizontal shaft 44 mounted in suitable bearings 45 and 46 on the top plate of the bed frame. At its inner end the shaft 44 passes through a sleeve 47, which is supported in 10 the bearing 46, and carries at one end a pinion 48 and at its other end a gear 49. 50 is a pinion loosely mounted on the shaft 44 adjacent the bearing 45. 51 is a clutch block 15 slidably splined on the shaft 44 and arranged between the gear 49 and the pinion 50, said gear and pinion carrying clutch teeth 49^a and 50^a, respectively, which co-operate with the teeth of the clutch block 51. A suitable hand lever 52 is provided 20 to shift the clutch 51 on the shaft 44. When the clutch is in the position shown in Fig. 1, the pinions 48 and 50 and the gear 49 all turn freely on the shaft 44, but by shifting the clutch into engagement with the gear 49, the latter and the pinion 48 are caused 25 to rotate with the shaft, and by shifting the clutch into engagement with the pinion 50 the latter is caused to rotate with the shaft while the pinion 48 and gear 49 turn freely 30 thereon.

A countershaft 53 is mounted parallel to the shaft 44 in a suitable bearing 54 on the top plate of the bed frame. At its outer end the shaft 53 carries a gear 55 that meshes 35 with the gear 50, and at its inner end it carries a pinion 56 that meshes with the gear 49. The pinion 48 meshes with the spur gear 33 which is secured to the winding drum shaft 29.

40 By means of the gearing described, it will be seen that the winding drum 18 can be driven at either of two speeds from the motor 34. When the clutch 51 is thrown into engagement with the pinion 50, the drum will be driven through the countershaft 53 at a low speed, and when the clutch 51 is thrown into engagement with the gear 49, the countershaft will run idle and the drum will be driven at a high speed. The 45 motor is, of course, disconnected from the drum 18 when the clutch 51 is in its intermediate position.

For the driving of the cutter chain there is a pinion 58 which is fast on the shaft 38 55 and which meshes with a gear 59 which is mounted concentric with the sprocket wheel 15 and is connected thereto by a suitable disengageable clutch which need not be described in detail as any form of clutch can 60 be used as far as my present invention is concerned.

When the cutting apparatus has been projected into the coal and the machine is being fed or propelled laterally by the tension 65 of the feed cable 19, the reaction of the coal

against the cutters is such that the outer end of the machine tends to swing forward more rapidly than the inner end of the bed frame advances. To prevent this and maintain the machine at a proper working angle 70 to the face of the coal, I provide the following devices. 60 is a cable winding drum rotatably mounted on a bracket 61 which is secured to the frame of the motor 34. 62 is a retarding cable which has one end connected to the winding drum 60 and is adapted to be extended rearward and to have its other end connected to a suitable abutment, such as a jack. In mounting the drum 60 I provide a journal or stud shaft 63 which 80 is carried by the bracket 61 and which fits the bore of the hub of the drum. A screw bolt 64 serves to hold the drum in position on its shaft.

To control the paying out of the retarding cable as the machine moves along the face of the coal, I provide the drum 60 with a friction brake by means of which any desired amount of resistance may be opposed to the rotation of the drum. The drum is 90 formed on its inner side with an annular rim 65 and upon the cylindrical outer surface of the rim is mounted a brake band 66. Clamping lugs 67 and 68 are riveted or otherwise suitably secured to the respective 95 ends of the brake band. These lugs are perforated to receive a clamping bolt or screw 69 and the lug 68 is slotted to receive a nut 70. This nut, when the parts are in position as shown in Figs. 9 and 10, engages the 100 bottom of the slot formed in the lug 68 so that it cannot turn. By turning the bolt 69 one way or the other, the brake band can therefore be tightened or loosened as desired. A handle 71 is pivotally secured to the end 105 of the bolt 69, and by means of this handle a partial rotation of the bolt can be made, and then by swinging the handle on its pivot, the turning movement can be continued. The lug 67 is formed with a vertical extension or flange 67^a which is apertured so as to pass over a cylindrical boss 72 on the bracket 61, and the brake band is thus prevented from being bodily displaced.

In addition to the friction brake I provide 115 a positive lock for the drum 60. A locking pin 73 is slidably mounted in the bracket 61, as shown in Figs. 9 and 10, in position to engage any one of a series of holes 74 formed in the adjacent face of the drum 60 120 or of its extension 65. The pin 73 is pivotally connected to a hand lever 75 by means of which it can be readily moved into and out of locking position.

It will be seen that when the free end of 125 the cable 62 is made fast to an anchoring device and the brake band 66 is suitably adjusted, a retarding force is applied to the outer end of the machine which serves to balance the reaction of the coal on the cut- 130

ters, and that this retarding force may be varied as desired by adjusting the brake band to vary the resistance to the rotation of the drum 60 as it pays out the retarding cable 62.

At various points on the bed frame of the machine I provide idler guide sheaves over which the feed cable 19 can be passed in various ways when it is desired to move the machine about over the floor of the mine by its own power. On the left side of the bed frame I mount a sheave 76 and on the right side a similar sheave 77, and on the outer end of the bed frame I mount sheaves 78, 79 and 80.

The operation of the machine will now be readily understood. The machine, on being brought into the mine room, is unloaded from the truck and brought to the face of the coal near one of the ribs. Assuming that it is desired to have the machine cut from right to left, the machine would be brought to the face adjacent the right rib as shown in Fig. 12. The first operation ordinarily is the making of the sumping cut by thrusting the cutting apparatus endwise into the coal. In doing this the machine must be guided and this can be done in various ways. The method indicated in the drawings involves the use of a jack 81 which is passed through the longitudinal slot in the cutter frame with its lower end engaging the floor and its upper end engaging the roof of the mine. This jack having been set as indicated in Fig. 12, the feed cable 19 is passed outward, over the guide sheaves 78, 79 and 80 and thence inward and to a jack 82 to which its end is secured. The motor having been started and the cutters thrown into operation, the clutch 51 is thrown into engagement with the pinion 50, thus driving the cutters and turning the winding drum 18 at slow speed. The tension on the cable 19 draws the machine inward against the coal, forcing the cutter frame under the coal as the latter is cut away. The combined action of the cable tension and reaction of the cutters as the entering cut begins, is to throw the inner end of the cutter frame to the right and the outer end to the left. This action is counteracted by the guiding effect of the jack 81 and the draft of the cable on the outer right hand corner of the bed frame of the machine.

When the machine has been advanced fully under the coal, the cable 19 is disengaged from the jack 82 and stretched along the face to the left rib where it is made fast to an anchor or jack 83, the winding drum 18 having first been freed from its shaft 29 by disengaging the clutch 18^b—18^c so that the cable can easily be unwound. Next the retarding cable 62 is made fast to the jack 82 and the machine is again started. At the beginning of the side cut, the outer winding

drum 60 is locked fast either by means of the friction brake or by means of the lock pin 73, thus making the outer end of the machine a pivot point, while the cutter bar is swung forward by the winding up of the propelling cable 19. As soon as the machine is thus swung around to the proper angle for side cutting, the lock on the retarding drum is removed and the friction brake set so that it will allow the drum to pay out the cable 62 under a suitable resistance to maintain the machine at the proper angle to the coal face as the undercut proceeds. As the machine moves along the face, the buffer 32 engages the face of the coal and prevents the bed frame from binding in the edge of the kerf or from being obstructed by reason of the uneven character of the coal face.

As the undercutting proceeds along the face of the coal, the nature of the material encountered by the cutters may vary from time to time thus varying the resistance to the advance of the machine. If softer material is encountered, the reaction on the cutters is less and the retarding action of the drum on the outer end of the machine may be too great, while if harder material is encountered, the reaction on the cutters being increased, the retarding force on the outer end of the machine will be insufficient and it will tend to swing forward too rapidly. All of these varying conditions are readily met by the machine runner by means of the control devices associated with the retarding drum 60. By simply adjusting the brake band 66, he is enabled to decrease and increase the resistance to the rotation of the drum at will. When softer material is encountered, he can diminish the tension of the brake band, and when harder material is encountered, the tension of the brake band can be increased; and thus the machine can be swung from time to time so as to maintain it in the desired angular relation to the coal face.

Obstructions, such as sulfur balls, or the like, are sometimes encountered which it is desirable to cut over by guiding the machine upward on skids and blocks and then downward again to the normal level. My improved cable guide devices are very advantageous in this connection, for when the machine has been thus guided upward, it can be deflected downward again by the positive draft of the propelling cable 19 exerted on the roller 22; I believe I am the first to make adequate provision for this purpose.

When the undercut is completed, the cable 62 is wound upon its drum 60, and the cable 19, having been disengaged from the jack 83, is carried to some point adjacent the truck where it is desired to reload the machine and there made fast to an anchor or jack. In thus extending the cable rearward, it is passed over the guide sheaves in such man-

ner as to give a desired line of draft on the machine. In thus moving the machine about in the room, the clutch 51 is thrown so as to drive the drum 18 at its higher speed which is more suitable for this purpose than the lower speed.

In Figs. 16 and 17 I have shown my improved machine when cutting from left to right. To change the machine for this purpose, it is only necessary to reverse the cutter bits in their sockets in the manner previously described, rewind the feed cable 19 in the opposite direction on its drum 18 and carry it off to the right between the guide sheaves 20 and 21 on the right side of the machine, rewinding the retarding cable 62 in the opposite direction, and throw the reversing switch 35 so that the motor will be driven in the opposite direction. These changes having been made, it will be seen that the machine can be handled and operated so as to cut from left to right in a manner precisely analogous to that in which it is handled and operated when side cutting from right to left.

What I claim is:—

1. In a mining machine, the combination of a bed frame, cutting apparatus having reversible cutters projecting from the inner end thereof, a winding drum on the bed frame, a propelling cable having one of its ends connected to the winding drum and being adapted to be wound thereon in either direction, idler guide means at each side of the bed frame near the inner end thereof over which the propelling cable can be passed and caused to exert a draft either toward the right or toward the left on the inner end of the bed frame, a motor on the bed frame to drive the said winding drum and the cutting apparatus, means for reversing the direction in which the winding drum and cutting apparatus are driven by the motor, and means adapted to exert a retard-

ing draft on the outer end of the bed frame 45 either toward the left or toward the right.

2. In a mining machine, the combination of a bed frame, cutting apparatus having reversible cutters projecting from the inner end thereof, a winding drum on the bed frame, a propelling cable having one of its ends connected to the winding drum and being adapted to be wound thereon in either direction, idler guide means at each side of the bed frame near the inner end thereof 55 over which the propelling cable can be passed and caused to exert a draft either toward the right or toward the left on the inner end of the bed frame, a motor on the bed frame to drive the said winding drum 60 and the cutting apparatus, means for reversing the direction in which the winding drum and cutting apparatus are driven by the motor, and guide devices comprising a retarding cable adapted to be extended 65 either toward the left or toward the right from the outer end of the bed frame and means for paying out the retarding cable as the machine advances.

3. In a mining machine, the combination 70 of a bed frame having an upstanding buffer extension across the inner end, said extension being formed in two separable parts, cutting apparatus projecting from the inner end of the bed frame, means comprising a 75 cable winding drum for propelling the machine along the face of the coal, a shaft on which said drum is mounted, and bearing supports for said shaft one of which is formed partly in one part and partly in 80 the other part of the said buffer extension.

In testimony whereof, I affix my signature, in presence of two witnesses.

EDWARD L. HOPKINS.
